UNITED STATES PATENT OFFICE
CERTIFICATE OF CORRECTION

Patent No. D-229,018 Dated November 6, 1973

Inventor(s) William E. Howard

It is certified that error appears in the above-identified patent
and that said Letters Patent are hereby corrected as shown below:

Page 1 - Assignor

The stated assignor of "Asta-Werke Aktiengesellschaft,
Chemische Fabrik of Brackwede, Westfalen, Germany"
is incorrect and should read --Materials Handling
Systems, Inc., West Hartford, Connecticut--

Signed and sealed this 11th day of June 1974.

(SEAL)
